UNITED STATES PATENT OFFICE.

HENRY P. FEISTER, OF PHILADELPHIA, PENNSYLVANIA.

PAPER-CUTTING MACHINE.

SPECIFICATION forming part of Letters Patent No. 319,473, dated June 9, 1885.

Application filed May 26, 1883. (No model.)

To all whom it may concern:

Be it known that I, HENRY P. FEISTER, of the city of Philadelphia, county of Philadelphia, and State of Pennsylvania, have invented 55 an Improvement in Paper-Cutting Machines, of which the following is a specification.

My invention has reference to paper-cutting machines; and it consists in certain improvements, all of which are fully set forth in the following specification, and shown in the accompanying drawings, which form part thereof.

The object of this invention is to provide suitable clamping and cutting mechanism to 15 a paper-cutting machine, whereby simplicity and perfect action is attained and the paper to be cut is clamped with a power proportional to its thickness, the said power being automatically adjusted.

20 In the drawings, Figure 1 is a front elevation of my improved paper-cutting machine. Fig. 2 is a rear elevation of same. Fig. 3 is a sectional elevation of same on line xx . Fig. 4 is a sectional elevation of the vacuum and pressure generating mechanism, and Fig. 5 shows plan views of the packing or resistance used in said vacuum apparatus to prevent 25 ready ingress of air.

A is the frame, and A' the cutting-table.

30 B is a worm-wheel, which is secured to a shaft, C, carried in a bearing, D, on frame-brace D'.

E is a worm-wheel meshing with worm-wheel B, provided with clutch-teeth e , and 35 supported loosely upon the driving-shaft E', which is provided with simply a fast pulley, F, or also with a loose pulley, F'.

e' is a clutch, which meshes with the clutch-teeth e and reciprocates upon shaft E', but rotates with it by means of the feather or key e^2 . This clutch e' is moved by a sliding bar, G, which may be shifted by a hand-lever, G'.

To retain the clutch in or out of action I provide a spring, H, having a tooth, h, which 45 springs over the A-block H' and holds said clutch from moving by all ordinary jars, but allows it to be readily moved by hand.

G² is a bell-crank lever having one of its arms pivoted to the bar G and the other arm 50 ranged in such a position with relation to a cam, g, on the worm-wheel B as to be auto-

matically struck and throw back said bar G and clutch, so as to stop the machine. The worm-wheel B is provided with a crank-pin, b, carrying a sliding block, b', which slides in a slot, i, in the end of the cutter-actuating lever, I, which is pivoted at J to the frame A, and has its shorter arm I' preferably bent upward, so as to have a substantially horizontal movement at its free end. Also pivoted to 60 pin J is a lever, K, of similar construction to I, with the exception that its end k has no slot and simply rests upon the pin b, this lever being adapted to actuate the clamp.

Working in the guide-slots A² of the frame 65 A is the cutter-plate P and clamp-plate Q. The cutter-plate P carries the knife or cutter P', and has oblique slots p at each end, through which pins p' pass, the said pins being stationary and secured to the frame. This plate 70 is connected to the arm I' by a link, O. The upper ends of the slots p may have rubber cushions p², to prevent the knife cutting too deeply into the table should any derangement of the operating mechanism take place. The 75 plate Q is guided obliquely and downward by slots q, also adapted to work on pins p', and is connected with the arm K' by link O'. The lower edge of plate Q is provided with a rib, Q², which fits a groove in the clamp Q', and 80 thereby carries it, the said clamp being guided vertically and without lateral movement by the frame-slot A². To lessen the friction between plate Q and clamp Q', I interpose 85 anti-friction-rollers R, which may be carried by either plate Q or clamp Q'. The cylinder L is pivoted to lever K at k', and is provided with a piston, L', and piston-rod L², which latter extends downward, and is pivoted by a pin, i', to the arm I' secured to or forming a 90 part of lever I. The lower end of the cylinder L is provided with inlet-valve N' and outlet-valve N, which latter may be adjusted to any pressure found most desirable by screwing down the nut n' upon the spring n². The 95 upper end of cylinder L is also provided with an inlet-valve, N', and an outlet-valve, N, the inlet-valve being made adjustable by a stem, n, nut n', and spring n², to resist any desired vacuum.

100 M is a resistance device, also secured to the upper end of the cylinder, and consists of a

cylinder, M', secured to the cylinder-head, which has a small hole, l, opening into said cylinder. In this cylinder M' are placed a series of disks of leather, m', and felt m, arranged alternately, the leather having notches m', which are arranged also alternately, causing the air which circulates through them to take a circuitous or S route. The upper end of this cylinder M' is closed with a screw-
10 plug, M², having a small hole, m², for the passage of air. By screwing the plug more or less tightly down upon the disks the resistance offered to the passage of air is increased or diminished.

15 In place of leather disks m' metal disks may be used.

I do not limit myself to the details of construction shown, as they may be modified in various ways without departing from my in-
20 vention.

If desired, the lower end of the cylinder L may be open to the atmosphere, in which case the pressure of the atmosphere alone is enabled to act through the creation of a partial
25 vacuum above the piston L'; or the lower end of the cylinder may be closed, as shown, and the upper end left open, in which case the power exerted by compressing the air would alone be utilized to clamp the paper; but I
30 prefer to close both ends.

The operation is as follows: The shaft E' being rotated by the wheel F, the paper is placed upon the table A'. The lever G' is then pressed in, throwing the clutch e' into action, 35 rotating the worm E and worm-wheel B. This causes the crank-pin b to move in a circle, depressing the levers I and K, lowering both the cutter P' and clamp Q' simultaneously until they reach the paper. As soon as the paper
40 arrests the downward movement of the clamp Q', and consequently the lever K, the cylinder L is held stationary, and the continued movement of the crank-pin b causes the piston L' to be moved in the cylinder L, creating a par-
45 tial vacuum at the upper end and pressure on the lower end. This pressure exerted on the lower end of the cylinder L, assisted by the pressure of the atmosphere upon the upper end, (which latter is enabled to be felt through
50 the production of said partial vacuum within the upper part of said cylinder,) causes said cylinder to be forced down, and this in turn forces down the lever K, thereby tending to clamp the paper firmly. To prevent too great
55 a vacuum being produced, the resistance device M is used, which allows a very small supply of air, and if the machine be driven too rapidly and the difference between the move-
60 ments of the cylinder L and its piston L' be
65 very great, or if the resistance be stopped up, there is liability to breakage, and to prevent this the valve N' is used on the vacuum end of the cylinder, and the pressure-valve N on the bottom of the cylinder. As the parts re-
gain their original positions any air above the piston is forced out by valve N, and any tendency to a vacuum below the piston is removed

by the influx of air by valve N'. The greater the thickness of paper to be cut the greater is the clamping action, and vice versa, for upon this depend the variations in the relative movements of the cylinder L and its piston L'. After the paper is cut and the parts return to their normal or original position, the cam g strikes lever G' and throws the clutch e' out of action, thereby automatically stopping the machine with the paper unclamped.

Having now described my invention, what I claim as new, and desire to secure by Letters Patent, is—

1. In a paper-cutting machine, the combination of a paper-clamp, a cutter, mechanism, substantially as set forth, to operate said cutter, vacuum-creating mechanism, substantially as set forth, connecting devices between said mechanism for operating the cutter and vacuum-creating mechanism, and between the latter and the clamp, whereby said vacuum-creating mechanism acts upon the paper-clamp to clamp the paper, substantially as and for the purpose specified.

2. In a paper-cutting machine, the combination of a paper-clamp, a cutter, mechanism, substantially as set forth, to operate said cutter and create a partial vacuum to allow the pressure of the atmosphere to act, and means, substantially as described, arranged to be acted on by said atmospheric pressure through the agency of the above mechanism to cause said clamp to press down upon the paper, substantially as and for the purpose specified.

3. In a paper-cutting machine, the combination of a paper-clamp, a cutter, mechanism, substantially as set forth, to operate said cutter, mechanism, substantially as described, to create a partial vacuum to allow the pressure of the atmosphere to act to clamp the paper, a relief device to limit the extent of vacuum produced, and connecting mechanism, substantially as set forth, whereby said atmospheric pressure acts upon the paper-clamp to cause it to clamp the paper, substantially as and for the purpose specified.

4. In a paper-cutting machine, the combination of a paper-clamp, a cutter, mechanism, substantially as set forth, to operate said cutter, mechanism to create a partial vacuum, and pressure-creating mechanism, substantially as set forth, connecting mechanism, substantially as set forth, whereby the atmospheric pressure made apparent by said partial vacuum and pressure-creating mechanism acts upon the paper-clamp to cause it to clamp the paper, substantially as and for the purpose specified.

5. In a paper-cutting machine, the combination of a paper-clamp, a cutter, mechanism, substantially as set forth, to operate said cutter, mechanism, substantially as set forth, for creating a partial vacuum, and compression of air, relief devices, substantially as described, to limit the extent of vacuum produced, and connecting mechanism, substantially as described, whereby the atmospheric pressure

made apparent by said partial vacuum and pressure-creating mechanism acts upon the paper-clamp to cause it to clamp the paper, substantially as and for the purpose specified.

5 6. The combination of wheel B, having crank-pin *b*, means, substantially as described, to rotate said wheel, lever K, link O', plate Q, having oblique slots *q*, pins *p'*, clamp Q', connecting mechanism between said wheel B 10 and lever K, and frame A, having a guide-slot, substantially as and for the purpose specified.

7. The combination of wheel B, having crank-pin *b*, means, substantially as described, 15 to rotate said wheel, lever K, link O', obliquely-moving plate Q, having oblique slots *q*, pins *p'*, vertically-moving clamp Q', connecting mechanism between said wheel B and lever K, rollers R, and frame A, having a 20 guide-slot, substantially as and for the purpose specified.

8. The combination of wheel B, having crank-pin *b*, means to rotate said wheel, levers I and K, links O and O', plate Q, having oblique slots *q*, plate P, having oblique slots *p*, knife P', pins *p'*, clamp Q', frame A, having a guide-slot, and means, controlled by the movement of lever I, to cause the clamp to firmly clamp the paper, substantially as and 30 for the purpose specified.

9. The combination of wheel B, having crank-pin *b*, means, substantially as described, to rotate said wheel, levers I and K, links O and O', plate Q, having oblique slots *q*, plate 35 P, having oblique slots *p*, knife P', pins *p'*, clamp Q', frame A, having a guide-slot, cylinder L, piston L', piston - rod L², and a resist-

ance device, substantially as described, to control the passage of air into said cylinder, substantially as and for the purpose specified. 40

10. The combination of crank - wheel B, having pin *b*, lever I, having slot *i*, lever K, cylinder L, having resistance device M, and valves N N', as set forth, piston L', and piston-rod L², the cylinder being pivoted to lever 45 K, and piston-rod to lever I, substantially as and for the purpose specified.

11. The combination of levers I and K, means, substantially as described, to oscillate lever I, cylinder L, pivoted to lever K, piston 50 L', piston-rod L², pivoted to lever I, and resistance device M, consisting of cylinder M', disks *m* and *m'*, and plug *m*², substantially as and for the purpose specified.

12. In a paper-cutting machine, the combination of a paper-clamp, a cutter, mechanism, substantially as specified, to operate said cutter, pressure - creating devices, substantially as set forth, connecting mechanism between said mechanism for operating the cutter and the pressure-creating mechanism, and between the latter and the clamp, whereby said pressure-creating mechanism acts upon the paper-clamp to clamp the paper with a pressure proportional to the thickness of the 65 paper to be clamped, substantially as and for the purpose specified.

In testimony of which invention I hereunto set my hand.
